Primary Examiner — Marie D. Fast Horse(74) *Attorney, Agent, or Firm* — McDonnell Boehnen Hulbert & Berghoff LLP(57) **CLAIM**

The ornamental design for a cradle for a point-of-sale terminal, as shown and described.

DESCRIPTION

FIG. 1 is a bottom front perspective view of a cradle for a point-of-sale terminal according to my new design;

FIG. 2 is a top front perspective view thereof;

FIG. 3 is a second top perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines in the drawings depict parts of the cradle for the point-of-sale terminal that form no part of the claimed design.

1 Claim, 4 Drawing Sheets(56)
